(57) **CLAIM**

The ornamental design for an actuator of a seat belt buckle, as shown and described.

DESCRIPTION

FIG. 1 is a top side perspective view of an actuator of a seat belt buckle showing my new design;

FIG. 2 is a bottom side perspective view of the actuator of a seat belt buckle as shown in FIG. 1;

FIG. 3 is a front elevational view of the actuator of a seat belt buckle as shown in FIG. 1;

FIG. 4 is a rear elevational view of the actuator of a seat belt buckle as shown in FIG. 1;

FIG. 5 is a left side elevational view of the actuator of a seat belt buckle as shown in FIG. 1;

FIG. 6 is a right side elevational view of the actuator of a seat belt buckle as shown in FIG. 1;

FIG. 7 is a top plan view of the actuator of a seat belt buckle as shown in FIG. 1; and,

FIG. 8 is a bottom plan view of the actuator of a seat belt buckle as shown in FIG. 1.

1 Claim, 6 Drawing Sheets
